UNITED STATES PATENT OFFICE

JOSEPH J. HENZE, OF DETROIT, MICHIGAN, ASSIGNOR TO A. BACKUS JR. & SONS, OF DETROIT, MICHIGAN, A CORPORATION OF MICHIGAN

PACKING CRATE

Application filed June 15, 1928. Serial No. 285,515.

The present invention pertains to a novel crate for shipping and generally transporting bread. The crates are subject to extremely rough usage, in being tossed from the trucks to express cars or to ferries. They are usually piled to the ceiling and the manner of piling consists of tossing the crates of the higher tiers into place, and, it is not unusual for the higher of the tiers to crash to the floor. This manner of handling and rough usage necessitates a light crate and yet of extreme durability. The present invention discloses a light weight crate constructed of panels. The panels are constructed of slats which are interlaced by wire, providing sufficient reinforcing to withstand the ordinary rough usage.

The crates are constructed of panels which are of standard sizes and thereby subject to rapid assembly with a comparatively small amount of labor. This assembly feature reduces the freight charges and storing charges prior to the box being used. It provides that the panels may be compactly piled and stored, occupying a mere fraction of the space which they occupy when assembled.

The bread within the crates which is often still warm, in being subjected to this rough usage is quite commonly crushed, and the value materially decreased. The present invention provides a floating partition which absorbs considerable of the shock and which supports the weight of the upper loaves when the crate is placed upon its end. In this manner the loaves are preserved in their normal state and are not crushed by the weight of the upper loaves.

The manner in which I attain these objects is fully disclosed by way of example in the following description with reference to the accompanying drawings in which

Fig. 1 is a perspective view of the crate with the cover partly broken away and with the corner gussets removed.

Fig. 2 is a perspective detail of an upper corner of the crate showing the attachment of the gusset;

Fig. 3 is a perspective detail of a lower corner of the crate.

Fig. 4 is an enlarged detail of one of the partition supporting members, and

Fig. 5 is an enlarged detail showing manner of interlacing the reinforcing wires.

In the drawings, the numeral 1 is employed to designate the end panels, 2 indicates the side panels, 3 the bottom panel and 4 the cover which is provided with suitable hinge members (not shown). The panels are constructed of frame members 5 to which are attached slats 6. The slats are attached by the staples 7 which are driven through the slats and into the frame members. The reinforcing wire 8 is retained by the staples 7 for attaching the slats together.

The exterior reinforcing wire 9 is attached to the frame members and extended transversely of the slats and is retained by the interlacing wire 10 which is attached at the ends on the inside of the panel and is woven between the slats to entwine the wire 9 and in this manner the slats are securely attached to the wire as is clearly illustrated in Fig. 5 of the drawings.

This manner of reinforcing attaches the slats securely together and gives considerably increased durability, thereby permitting the panels to be constructed of extremely light material.

The end panels 1 are provided with drill holes 11 which correspond with the drill holes 12 of the bottom panel and similarly the side panels 2 have the drill holes 13 corresponding with the drill holes 14 of the bottom panel.

In the assembly the end panels are placed upon the bottom panel and bolts 15 passed through the drill holes 11 and 12 and the end panel is secured to the bottom by means of these bolts 15. Similarly the side panel is placed upon the bottom and bolts 16 are passed through the drill holes 13 and 14, securing the side panels to the bottom panel. The side panels are constructed to overlap the end panels as is indicated in Fig. 1 of the drawings, and are provided with the corresponding drilled holes 11' through which the bolts 12' are inserted to secure the ends of the panels together.

The upper corners are further secured together by gussets 17 which attach and rein-

force the upper corners of the panels. The lower edges of the panels are likewise reinforced and further attached to the bottom panel by the gussets 18 which, in addition to reinforcing the corners, serve as a buffer to the corners as well.

Attached to the interior of the side panels 2 are the brackets 19, suitable to receive a link 20 which is received at its other end by a bracket 21 secured to a partition 22. This connection permanently attaches the partition within the crate and permits a floating motion. The loaves of bread 23 are placed upon their ends. The loaves are not usually of uniform size and the floating partition enables the loaves to be snugly packed regardless of various sizes.

The floating partition, in addition to permitting loaves which are not uniform in size to be packed, prevents them from bouncing around during shipment. It further relieves the loaves when the crate is placed on end. In this manner bread may be shipped without damage in light crates of extreme durability.

The method of assembling the crates in the manner above described provides that the crates may be shipped to the customer, or kept in a store-room in knock down form. The assembly by the customer is a comparatively simple undertaking by reason of the crate being constructed of standard size panels which are previously provided with drilled holes. The drilled holes are provided in positions which correspond with the drilled holes of the abutting panel, the panels being secured together by bolts being placed in the drilled holes. This method of assembly provides a light crate of extreme durability, of considerably more substantial character and adapted for more rapid assembly than crates formed by nailing the members of the crate together.

Although a specific embodiment of my invention has been disclosed it will be understood that such alterations in the details of construction may be made as fall within the scope of the appended claims.

What I claim is:

1. A crate comprising bottom, side and end panels secured together, brackets secured to the inner surfaces of certain of said panels, links carried by said brackets, and a partition having brackets adapted to receive the opposite ends of said links.

2. In a crate having a hinged cover, a bottom panel, side and end panels attached to said bottom panel and secured to each other at their upper corners, brackets secured to the inner surfaces of said side panels, links carried by said brackets, a partition, and brackets mounted upon said partition and receiving the opposite ends of said links.

In testimony whereof I affix my signature.

JOSEPH J. HENZE.
